D. W. HAMLIN.
IRONING BOARD.
APPLICATION FILED NOV. 9, 1912.

1,090,708.

Patented Mar. 17, 1914.

UNITED STATES PATENT OFFICE.

DENVER W. HAMLIN, OF LOS ANGELES, CALIFORNIA.

IRONING-BOARD.

1,090,708.

Specification of Letters Patent. Patented Mar. 17, 1914.

Application filed November 9, 1912. Serial No. 730,368.

To all whom it may concern:

Be it known that I, DENVER W. HAMLIN, a citizen of the United States, residing at Los Angeles, in the county of Los Angeles, State of California, have invented certain new and useful Improvements in Ironing-Boards; and I do hereby declare the following to be a full, clear, and exact description of the invention, such as will enable others skilled in the art to which it appertains to make and use the same.

This invention has special reference to ironing boards and the essential object thereof is evolved in the provision of an ironing board designed to removably engage a table or other similar support at the edge portion thereof, whereby the device will serve with great facility for the laundrying of clothes to be slipped over the board.

A more specific object of the invention is the provision of a folding ironing board of the above class in which a supporting leg is provided to pivotally and adjustably connect to the board and extend through a slot 25 therein, the upper end of the leg being provided to support an iron while novel clamping means are movably arranged and adjustable on the leg above the board to properly receive the table therebetween so that downward pressure on the board will cause the parts to tightly grip the table.

With the above and other objects in view, the invention resides more particularly in the peculiar combination and arrangements 35 of parts as will be illustrated in the accompanying drawings and described in the specification, although the invention is protected for all desirable changes and uses within the scope of the invention as claimed.

Figure 1 is a perspective view showing the edge portion of a table with the ironing board attached thereto. Fig. 2 is a side elevation of the device partly in section. Fig. 3 is a cross sectional view taken on the line 3-3 of Fig. 1. Fig. 4 is a fragmentary detail view of the supporting leg removed. Fig. 5 is a bottom plan view of a fragmentary portion of the board. Fig. 6 is a detail perspective view of a clamping member slidably carried by the leg.

In illustrating the preferred embodiment of the invention, there is shown a table 10, to the edge portion of which the ironing board 11 is attached. This board is provided at its enlarged end with a central slot 12, the end wall 13 of which is under-

cut or beveled as shown and such enlarged end is adapted to engage under the table edge whereby the tapered free end thereof will extend outwardly for the convenient application of the clothes to be laundried.

A foldable leg 14 is provided for the board and at its upper end movably engages through the slot 12. A pair of pivot cleats 15 are rigidly attached to the bottom face of the board longitudinally thereof in spaced relation, so that their inner faces will align with the side walls of the slot and these cleats are provided with a plurality of transversely registering perforations 16 adapted to align with one of a plurality of transverse perforations 17 in the supporting leg whereby the same may be adjusted between the cleats to properly engage the table edge, by means of a pivot pin 18, according to the thickness of such edge or other support, such as a window sill. When thus positioned, the supporting leg is disposed at an incline beneath the board and has on its upper end a supporting member 19 which is removably and turnably attached to said end for supporting an iron. This support comprises a section of metal having a plurality of side flanges 20 which retain the iron from displacement. In order to securely anchor the board to the table edge or sill, the top edge of the leg above the table is provided with a plurality of ratchet notches 21 and a rectangular sleeve 22 is slidable on the leg and has a substantially triangular projection 23 at its lower portion to conform to the top face of the table.

The top portion of the sleeve is provided with a slot 24 extending transversely thereof and the side portions of the sleeve are bent up in overlapped relation at the bottom edge thereof to form a pivot yoke 25 in the side portions of which a catch 26 is pivoted. The free end of the catch operates through the slot 24, being bent inwardly for this purpose, while a leaf spring 27 is anchored to the sleeve and bears upwardly against the opposite extremity of the catch to hold the same engaged with the notches and permit adjustment thereof according to the thickness of the support gripped thereby. The adjustment of the board at different elevations to suit the desires of the different users of the board is also accomplished by the adjustment of the pivot pin 18 in the perforations 17 of the supporting leg. Fur-

thermore, it will be observed that the top portion of the sleeve 22 is extended downwardly on the leg in substantial channel form and serves as an abutment for the 5 catch and spring as well as to limit the tendency of the sleeve to move as if on a pivot, when pressure is being applied to the catch in disengaging the same.

I claim:

- 10 The combination with an ironing board having a slot in one end, of a supporting leg pivotally and adjustably mounted in said slot and projecting above the top face of said ironing board, said leg being substantially square in cross section at the top and being provided with a series of notches in one longitudinal edge, a casing of substantially square cross section slidably engaging on the upper end of said leg and 20 provided with substantially right angular side projections that depend below the cas-

ing and have the lower edges parallel with the top face of said ironing board, said edges being adapted to engage with the top face of a table or other support and co-operate with the pivot of said leg in supporting said ironing board, a substantially U-shaped keeper on the upper edge of said casing, a slot in said casing in advance of said keeper, a rightangular catch pivoted within said keeper and engaging through said slot, and a leaf spring interposed between said casing and said catch and yieldably holding the working end of said catch selectively in engagement with one of said 30 notches.

In testimony whereof, I affix my signature, in the presence of two witnesses.

DENVER W. HAMLIN.

Witnesses:

LILLIAN DARLING,
ALLIE HOWARD.
